DEVICE FOR RAPIDLY MAKING CROSS-
SECTIONS OF FIBERS

John I. Hardy, Washington, D. C.

Application June 7, 1935, Serial No. 25,443

2 Claims. (Cl. 88—40)

(Granted under the act of March 3, 1883, as
amended April 30, 1928; 370 O. G. 757)

This application is made under the act of March 3, 1883, as amended by the act of April 30, 1928, and the invention herein described, if patented, may be manufactured and used by or for the Government for governmental purposes without the payment to me of any royalty thereon.

My invention relates to a device having a fiber slot for use in rapidly making cross-sections of wool and other fibers, and having a means for propelling fibers through the fiber slot. The only rapid method for making thin cross-sections of fibers is that described by me in Patent No. 2,011,444, August 13, 1935, application Serial No. 17,834, filed April 23, 1935, in which the fibers are held in a fiber slot in a threaded rod.

The object of my present device is to obtain rapidly good thin cross-sections of a large number of fibers, an advantage over the existing rapid method for making thin cross-sections of individual fibers.

I attain these objects by use of the device illustrated in the accompanying drawing in which Figure 1 is a top plan view of the entire device; Figure 2 is a side view of the entire device; Figure 3 is a detailed view of the mechanism for propelling fibers through the fiber slot.

The device involves the use of a metal plate 1, called the fiber holder. There is a fiber slot 2 in plate 1, extending a predetermined distance towards the center of the fiber holder. The second plate 3, called the slide holder plate, which may or may not be the same size as the first mentioned plate, also contains a slot 4 in which is rigidly affixed a flat surfaced metal slide 5, with a right angled flange 6, said slide extending sufficiently beyond the slide holder plate 3 to fill partially the above mentioned slot 2 in plate 1.

The metal slide consists of a thin metal plate so formed as to have a flange 6 extending at a right angle to the plate in such a manner that when the portion of the slide 5 which projects from plate 3 is inserted in slot 2 of plate 1, the aforementioned flange will be positioned on one side of plates 1 and 3 and the metal slide will partially fill slot 2. The portion of the slide 5 which enters slot 2, is of the same width as the thickness of plates 1 and 3, so that the plate 1 and the edge of slide 5 are in alignment when the slide is placed in slot 2 whereby a smooth surface is provided adjacent the fiber slot. Two metal U-shaped guides 7 are positioned on each side of metal plate 3 adjoining plate 1 to hold plate 1 and plate 3 in the same plane when the metal slide 5 is inserted in the fiber slot 2. Af-

fixed to the fiber holder 1 is a metal swivel 8 attached to approximately the central point on the upper surface of the fiber holder 1 by a screw 9. One end of the swivel has an overhanging arm 10. Passing through the overhanging arm 10 is propelling screw 11. The under arm 12 of the swivel, extending under the upper arm has a slot 13 which is in perfect alignment with the base end of the fiber slot 2 when the set screw 14 is screwed into the countersunk hole 17 in alignment with the fiber slot 2 of the fiber holder. There is positioned in the slot 13 of the under-arm a metal plunger 15 which is directly above the base end of the fiber slot 2. At the top of the metal plunger is affixed a metal disc 16 with a countersunk hole at its center point. Above this countersunk hole is the propelling screw 11 for moving the metal plunger 15 through the fiber slot 2. Under the metal disc 16 and around the metal plunger 15 is a coil spring 18 which raises the plunger 15 when the propelling screw 11 is raised. The movement of propelling screw 11 may be measured by graduating the head of the screw 11 as shown at 20 in Figure 1 and providing the upright index arm 19 attached to the upper 25 arm of the swivel.

To operate the device, the metal swivel 8 is swung to one side after releasing set screw 14; then small groups of fibers are inserted into the fiber slot 2 until it is filled to a greater depth 30 than the depth of the under arm slot 13, when the fibers are slightly compressed. Slide 5 is then inserted in slot 2 until the fibers are firmly held in the fiber slot. By means of a safety razor blade the fibers are cut off flush on both 35 sides of the fiber holder plate. Should the fibers appear compacted too closely, this condition may be overcome by pulling out slide 5 a short distance.

The swivel 8 is swung back into position until set screw 14 fits the countersunk hole 17 in the fiber holder 1. The propelling screw 11 is turned to advance the fibers slightly through the fiber slot 2. The ends of the fibers projecting through the fiber slot are cut off. The propelling screw 11 is again advanced slightly and the ends of the fibers are covered with a thin smear of cellulose acetate solution which is allowed to dry to a thin film over and around the ends of the fibers. This film containing the ends of the fibers is cut free from the fiber holder with a sharp safety razor blade. The film is then transferred to a glass slide, mounted in some suitable mounting medium and covered 55

with a cover slip. The cross-section of fibers is then ready for examination.

This device may be used to assist in the determination of fiber fineness, as well as in obtaining extremely thin cross-sections of fibers of a determined thickness.

Having fully disclosed my invention I claim:

1. A device for making cross-sections of fibers, comprising a plate, a fiber slot extending inwardly from an edge of the plate, a metal slide adapted to enter and fill the fiber slot except for a space at the base of said slot, a slide holder plate attached to one end of the slide, means to hold said two plates in alignment with each other when the slide is inserted in the fiber slot, a swivel having an overhanging arm and an under arm in alignment with each other, at one end thereof, said under arm having a slot in its free end, so mounted on the first mentioned plate that the slot in the under arm of the swivel may be brought into alignment with said space at the base of the fiber slot, means rigidly to hold said slots in alignment, a

plunger having a plunger plate at the lower end thereof adapted to enter the slot in the swivel and the base of the fiber slot, a propelling screw threaded through the overhanging arm to contact with the top of the plunger, tension means attached to the plunger between the arms of swivel to raise the plunger as the screw is raised and means to measure the movement of the propelling screw through the overhanging arm. 10

2. A device for use in making cross-sections of fibers, comprising a plate, a fiber slot extending from an edge of the plate, slide means in the slot to partially close the slot whereby a portion of the slot may be left clear at the base thereof, 15 an adjustable plunger plate adapted to enter the fiber slot at the base thereof, adjustable means attached to the first mentioned plate to suspend the plunger plate over the first mentioned plate in alignment with the base of the fiber slot and 20 means measurably to control the movement of the plunger plate in the fiber slot.

JOHN I. HARDY.
